MAHLON M. ZELLERS, OF KENT, OHIO, ASSIGNOR TO HIMSELF AND JAMES B. MILLER, OF SAME PLACE.

VALVE.

SPECIFICATION forming part of Letters Patent No. 237,794, dated February 15, 1881.

Application filed July 13, 1880. (No model.)

To all whom it may concern:

Be it known that I, MAHLON M. ZELLERS, of Kent, in the county of Portage and State of Ohio, have invented certain new and useful

5 Improvements in Valves; and I do hereby declare the following to be a full, clear, and exact description of the invention, such as will enable others skilled in the art to which it pertains to make and use it, reference being had 10 to the accompanying drawings, which form part of this specification.

In the drawings, Figure 1 represents in longitudinal vertical section a valve constructed according to my invention. Fig. 2 is a detached plan view of the valve-stem shown in 15 Fig. 1. Fig. 3 is a detached plan view of the guide-nut B. Fig. 4 is a view in side elevation of the same. Fig. 5 is a view in side elevation of the part C of the device shown in 20 Fig. 1. Fig. 6 is a plan view of the same. Fig. 7 is a view in side elevation of the valve proper with its screw and square shank. Fig. 8 is a view of the packing-spring g. Fig. 9 is a view in side elevation of the ring F, which 25 affords a rest to the spring g; and Fig. 10 is a plan view of said ring.

In the said drawings, A is a valve-chamber with its valve-seat a and valve-proper, a'.

B is a guide, constructed in the shape of a 30 nut, with male and female screw threads, as shown in the drawings, Figs. 1 and 4, and is provided with an opening, b, to prevent the rotation within it of the shank E of the valve, which shank is formed substantially in counter- 35 part of the opening b, through which it moves.

C is a shell for containing the valve-stems D and E, packing-spring g, and ring F. It has an inner surface formed in counterpart of the beveled portion d of the valve-stem D, and 40 the spring g, exerting a pushing-pressure, operates at all times to insure a tight joint at d.

D is the upper or boss section of the valve-stem, and it extends outside of the chamber C to admit of the attachment of a suitable 45 handle for manipulating the valve. The upper valve-stem section has the outer side of its lower portion cut away, and in the upper part of the annular recess thus formed between the cut-away portion and the casing the spiral 50 spring g is fitted. In the lower part of said re-

cess the independent ring F is fitted, and this ring provides bearing for the spring as the latter forces the valve-stem section upward or outward.

It will be seen that the stem D has only a 55 rotating motion within the chamber C, and is not permitted or designed to have any vertical or longitudinal movement.

The packing-spring g, as already intimated, pushing up upon the stem D, operates, in conjunction with the joint d, as an effectual packing.

I am aware that faucets have been constructed with a valve and valve-stem made in a single piece, the valve-stem being provided 65 with a collar to close the opening at the upper end of the casing, a spiral spring being arranged to encircle the valve-stem and retain the collar in close contact with the valve-casing. Said spiral spring rests upon a packing- 70 ring the edge of which engages with the reciprocating valve-stem. This construction of valve would be impracticable in the type of valve to which my improvement belongs, as an opening must necessarily be formed between 75 the two sections of the valve-stem, so that it would be practically impossible to employ a packing-ring fitting the reciprocating portion of the valve.

I am also aware that valves have been constructed with a two-part stem, one portion being provided with a screw-threaded socket, in which is received the screw-threaded end of the other portion of the valve-stem, the latter being provided with a spline to prevent the rotation of 85 the valve. In this construction of valve no packing is provided for preventing the escape of water through the joint of the valve-casing or past the non-reciprocating portion of the valve-stem. Hence I would have it understood that I make no claim to the construction of valve above referred to, but restrict myself to the particular construction and arrangement of parts shown and described.

In my improved construction of valve the 95 upper portion of the valve-stem is reduced in size near its lower end, thereby forming an annular chamber between the valve-stem and casing, in which chamber is placed a spiral spring, the upper end of which rests against 100

a shoulder on the valve-stem and retains its conical shoulder in snug contact with the valve-casing. The lower end of the spiral spring rests upon a cylindrical packing-ring and retains the lower edge thereof in close contact with the valve-casing, thereby preventing any escape of water through the joint of the valve-casing, while the cylindrical portion of the packing-ring fits snugly between the valve-casing and valve-stem, thereby insuring an extended packing which prevents the escape of water past the valve-stem and through the upper portion of the valve-casing.

My improved construction of valve is simple, effective, and durable.

What I claim is—

The combination, with the valve-casing, and guide-nut B, screwed therein, said guide-nut having an angular opening, b, formed therein,

of the valve provided with an angular valve-stem, E, which fits in the guide-nut B, the shell C screwed into the guide-nut, the valve-operating stem screw-threaded to receive the screw-threaded end of the valve-stem, and a ring, F, and spring g, interposed between the valve-operating stem and valve-casing, said ring being seated upon the upper portion of the guide-nut, and the spring bearing against an annular shoulder formed on the valve-operating stem, substantially as set forth.

In testimony whereof I have signed my name to this specification in the presence of two subscribing witnesses.

MAHLON M. ZELLERS.
